UNITED STATES PATENT OFFICE.

JOSEF HOFMANN, OF BAUMAROCHE, SWITZERLAND.

RECORDER FOR MUSICAL DYNAMICS.

Application filed May 5, 1925, Serial No. 28,158, and in Great Britain May 26, 1924.

This invention relates to recording devices for producing master music records in key-operated master musical instruments, such as recording pianos and the like, and has for 5 its object to provide a device for recording the actual pianistic touch on music records automatically during their production.

Tonal effects (dynamics) as produced by artistic player pianos are controlled by specially arranged perforations on the right and left side of the music record usually consisting of a perforated roll of paper.

In the known recording systems, usually these perforations are not applied to the 15 master or initial record by the recording artist himself, but are either recorded with the aid of a separate contrivance manipulated by another person listening to the artist during the recording period and applying the 20 dynamics according to his own judgment, or they are added afterwards. The actual touch of the recording pianist has therefore no effect upon the dynamic indications of the recording machine and consequently 25 the finished master record or roll from which the duplicates are made for the player piano lacks the individuality of the producing artist.

Now according to this invention, the 30 pianist is enabled by an automatic mechanism to record his own dynamics without interference by others by means of a device which is highly sensitive to the various degrees of the blow or blows as delivered by 35 his fingers, hands or arms. Each blow and its exact dynamic degree is transformed into corresponding record perforations or marks on the roll of paper and a roll thus made when used with a reproducing player piano 40 will therefore bring about or indicate a tonal picture identical to the pianist's original effort.

To this end the invention consists in a device which is so associated with the keyboard 45 of the recording key-operated musical instrument as to utilize the dynamic force imparted by the player individually to each key or to a number of keys of the keyboard to actuate mechanism adapted automatically 50 to control in a correspondingly suitable manner the means employed for effecting the dynamic perforation or marking of the record which is subsequently used to control the tonal expression of the reproducing 55 instrument. In this device the transmission and translation is by preference of a

mechanical kind and the operation of the actual perforating or marking mechanism is with advantage electro-magnetical.

Recording as well as reproducing player 60 pianos are, as a rule, divided into right and left dynamics; in other words, one half of the keyboard is dynamically controlled by perforations on the right hand side of the roll of paper, and the other half by perforations on the left hand side.

Accordingly the automatic dynamic device according to this invention is preferably 70 also divided into two, or rather, arranged in duplicate, one device being allotted to each half of the piano in order to enable right hand dynamics to be marked independently from left hand dynamics.

The instrumentalities that actually form 75 the record in the music sheet are of well known construction and are not illustrated nor required to be for an understanding of my invention.

The accompanying drawings illustrate by 80 way of example a construction of an automatic dynamic transmission device, embodying the invention and in which like parts are similarly designated.

Fig. 1 is a perspective view of the device 85 arranged at the left hand side of the recording piano; and

Fig. 2 an end view thereof.

Fig. 3 is a rear elevation of the control device, and

Fig. 4 a cross section on the line IV—IV 90 of Fig. 3.

Fig. 5 shows in a diagrammatic development, an example of the disposition of contacts over the surface of the control drum, whereby, according to the dynamic force applied to the keys, one or more of several 95 electric circuits are closed.

Fig. 6 is a cross-section of the plunger piston.

Below the keyboard A of a master musical 100 instrument and immediately underneath the white keys B and the black keys C, is pivotally mounted in bearings 1 a shaft 2 extending in two parts from the middle E-key to the right and left ends of the key board. 105 Each part of the said shaft 2 carries by means of arms 3, rigidly connected thereto at right angles to its axis, a bail or bar 4 located under the forward end of the black keys C. Directly above this bar each key 110 B and C has fixed to its underside a felt pad 5 acting as a shock absorber when in

depressing a key it strikes the bar 4. For each half of the key board therefore the shaft 2, arms 3 and bar 4 form a rigid rocking frame, for the transmission of the dynamics of the right and left key boards to the right and left hand side of the music sheet. These rocking frames are normally held in raised position by means hereinafter to be more fully described, and are caused to be rocked by any one or a number of the keys B or C to an extent corresponding to the amount of depression of the key or keys.

At the outer end of each of the said frames, the shaft 2 carries, rigidly secured thereto, a lever arm 6, having fixed to its free end, which is preferably formed as a segment a belt or steel ribbon 7 the other end of which is secured to a pulley 8 in such manner that when the lever 6 swings upwardly the ribbon 7 causes the pulley 8 to revolve against spring action. The pulley 8 is fast on a shaft 9 journalled between centres 10 which are mounted in standards 11, 11^a. The shaft carries fast on it a contact drum 12 of considerably larger diameter than the pulley 8 in order to obtain an appropriately magnified extent of the rotary movement on the circumference of the drum 12. Preferably, I do not use a circular pulley but a cam, so that the leverage for the initial or light impact will be greatest and gradually increase thus complementing the successively applied springs b' and so forth, to be described. Loosely mounted on the shaft 9 in juxtaposition to the drum 12 are a series of fingers a', . . . a¹¹ which normally are held in a fan like formation (see Fig. 1). The position of each finger is individually determined by an arm c forming part thereof and adapted under the influence of springs b' . . . b¹¹, one allotted and attached to a lug on each of said fingers to abut against a common stop pin 13 secured parallel with the shaft 9 to the standard 11.

The fingers a' . . . a¹¹ extend into the path of rotation of a pin 14 secured parallel with the shaft 9 to the face end of the drum 12. The pressure exerted on the pin 14 by the lowermost finger a' through the action of its spring b' is calculated to maintain the drum 12 in a neutral or balanced position against the tendency of the weight of the rocking frame, 2, 3, 4 to rotate the drum 12 in the opposite direction through the lever 6, belt 7 and pulley 8. To this end the spring b' is of such strength and its tension is preferably adjustable so that the rocking frame is normally held in perfect balance and is therefore sensitively responsive to the slightest pressure exerted upon it by any one of the keys when depressed by the player.

When therefore in the operation of any one of the keys B or C, the bail 4 of the

rocking frame is depressed, the lever 6 is caused to swing up through an equal angle and through the steel band or belt 7 rotates the pulley 8 and the drum 12 in the direction of the arrow x to a corresponding extent. In this rotary movement of the drum 12 and according to the extent thereof, the pin 14 engages in succession the fingers a' . . . a¹¹ and by swinging them about their fulcrums in opposition to the action of their springs b' . . . b¹¹ causing the latter to offer a gradually increasing resistance to the dynamic force exercised through the keys on the bar 4. Consequently when the resistance offered by the springs thus stressed balances the dynamic force referred to, the rotation of the drum is arrested. The dynamic force applied to the keys by the touch of the player thus controls the angle of rotation of the drum 12 and by suitably arranged contacts on the said drum renders it possible to effect the closing of electric circuits arranged to operate corresponding devices employed for marking or perforating the music roll.

The initial spring b' shall be strong enough to return all parts to initial position on the return movement and at the required speed. If the spring is strong enough for this, it is not sufficiently sensitive for a light touch and for this reason, I use the cam 9 to increase the initial leverage between the frame and drum.

It is evident that, in the event of greater or cumulative dynamic forces being applied to the keys when a plurality of the springs b' . . . b¹¹ becomes operative, the aggregate force of such springs is apt to effect too quick a return of the drum to its balanced or neutral position and is thus liable to allow insufficient time for the performance of the operations of the perforating or marking device. In order to counteract this, the piston rod 15 of a dashpot having an inner cylinder 16 and an outer cylinder 17 is connected to the pin 14. On the other hand, when the resistance of the springs in actual use at any one time is low, it is not necessary to retard the return action of the springs, and to this end in order to regulate the exhaust of such dashpot progressively in inverse ratio to the extent of the piston stroke the cylinder 16 has formed in its wall an exhaust slot 16^a gradually diminishing in width towards the top of the maximum piston stroke.

The piston 18 is constructed as shown in Fig. 6, and has two ports 19. The piston rod 15 passes loosely through the piston and has rigidly secured thereto a valve 20 and nut and washer 21. The distance between the valve 20 and washer 21 is slightly greater than the thickness of the piston so that the ports are open when the piston moves in one direction and are closed by

the valve 20 when moving in the opposite direction.

In the example shown the drum 12 in accordance with the extent of its rotary movements is adapted to close one or more electric circuits which actuate electric magnetic devices of known type for automatically perforating or marking the perforations for use in controlling the dynamics of a music roll.

10 In conformity with the adopted system of "dynamics" in music rolls, the apparatus illustrated in the drawings is assumed to be used in connection with instrumentalities which perforate or mark the "dynamics" in four rows at each side of the music roll. The perforations in each row represent a predetermined force so that perforations of several rows in alignment represent the aggregate of the forces of the particular rows.

20 Accordingly the apparatus employed for effecting the closing of the electric circuits is in this case provided with four stationary contact bushes or members d^1 , d^2 , d^3 , d^4 adapted to make contact with various combinations of insulated contact pieces arranged on the circumference of the drum 12. As shown in Fig. 5, the contacts on the drum are arranged in four circumferential rows e^1 , e^2 , e^3 , e^4 corresponding to the four predetermined "dynamics" of the music roll, so that in the rotation of the drum in the direction of arrow y , the contact pieces in the rows make contact with one or more of the spring contacts d^1 , d^2 , d^3 , d^4 thereby operating the perforating or marking devices denoting the aggregate "dynamics" corresponding to the force exercised on the key or keys by the players. Normally the spring contact members d^2 , d^3 , d^4 are not in conductive contact with the contacts on the drum 12. That is to say, contact d^1 is usually in contact with its contact when the drum is in its zero position.

25 Evidently the contacts may be arranged in any suitable manner and on any other appropriate carrier to meet different requirements of different systems of perforating and marking apparatus. Or the rocking frame may be mounted on knife edge bearings to enhance its sensitiveness and may be provided with means for adjusting the normal position of the rocking frame if desired. Moreover, the transmission of the movements of the lever 6 to the drum 12 may be effected by means of a toothed segment and pinion and generally speaking, various other structural modifications may obviously be made by those skilled in the art without departing from the spirit of the invention.

30 I claim—

1. The combination for a key-operated master musical instrument; mechanism associated with and movable by the depression of a key or the depression of a number of keys thereof according to the touch, and

movable in accordance with the touch the same extent with respect to any key, means to multiply said movement, and devices operated by said means for expression recording instrumentalities.

70 2. The combination for a key-operated master musical instrument; mechanism associated with and movable by the depression of a key or by the depression of a number of keys thereof according to the touch, means to multiply said movement, devices operated by said means for operating expression recording instrumentalities, and means to progressively add separate resistance to the operation of said mechanism.

75 3. The combination for a key-operated master musical instrument; mechanism associated with and movable by the depression of a key or the depression of a number of keys thereof, according to the touch, means to multiply said movement, a contact drum rotated by said means, and brushes contacting with the drum.

80 4. The combination for a key-operated master musical instrument; a balanced rocking frame associated with a plurality of the keys thereof for depression by a key or keys, means to progressively increase the resistance of said frame to movement in accordance with the impact of the key.

85 5. The combination for a key-operated master musical instrument; a rocking frame beneath the keys thereof, a drum, means to positively connect said frame and drum to impart partial rotation to the latter, spring means to progressively increase the resistance of said drum to rotation, said drum having means thereon for controlling dynamic recording means.

90 6. The combination for a key-operated master musical instrument; a rocking frame beneath the keys thereof, a drum, means to positively connect said frame and drum to impart partial rotation to the latter, spring means to progressively increase the resistance of said drum to rotation, said drum having means thereon for controlling dynamic recording means, and means to prevent the too rapid rotation of the drum.

95 7. The combination for a key-operated master musical instrument; a rocking frame, an arm extending from said frame, a drum rotated from said arm, a pin on the drum, and a plurality of spring-retracted fingers progressively engaged by said pin.

100 8. The combination for a key-operated master musical instrument; a rocking frame, an arm extending from said frame, a drum rotated from said arm, a pin on the drum, a plurality of spring-retracted fingers progressively engaged by said pin, and means to prevent the too rapid rotation of the drum.

105 9. The combination for a key-operated master musical instrument; a balanced rock-

ing frame arranged beneath and in the path of movement of keys thereof, a rotatable drum operated from said frame, a pin projecting from an end of the drum, pivoted, 5 spring-retracted fingers successively and angularly displaced and arranged to be successively engaged by said pin, and a dash-pot to retard the movement of said drum.

10. The combination for a key-operated master musical instrument; means associated with keys thereof to be moved in accordance with the player's touch, a drum rotated thereby, means to progressively increase the resistance to rotation of said drum and therethrough the resistance of 15 said means to operation, a dash-pot to retard the movement of said drum, and means cooperating with said drum for actuating mechanism for record dynamics on a music 20 sheet.

11. The combination for a key-operated master musical instrument; a rocking frame, an arm extending from said frame, a drum rotated from said arm, spring means 25 to return the drum to normal position and means to prevent the too rapid return movement of the drum.

12. The combination for a key-operated master musical instrument; mechanism associated with and movable by the depression 30 of a key or by the depression of a number of keys according to the touch, means to multiply such movement, devices operated by said means for operating expression recording 35 instrumentalities, and cam means

to progressively increase the resistance to the operation of said mechanism.

13. The combination for a key-operated master musical instrument; a rocking member arranged for actuation by a key or keys 40 of said instrument, a spring retracted drum and a variable leverage device between said member and drum.

14. The combination for a key-operated master musical instrument; a rocking member 45 arranged for actuation by a key or keys thereof, a contact drum, spring means to increasingly oppose the rotation of said drum from its zero position and means between said member and drum, and connected to both, to vary the operating leverage of said member with respect to the drum.

15. The combination for a key-operated master-musical instrument, mechanism associated with and movable by the depression 55 of a key or the depression of a number of keys thereof according to touch, and movable in accordance with the touch the same extent for any key, means to multiply the movement of said mechanism, devices successively coming into operation to progressively load said mechanism, and a member 60 operated by said means to control recording instrumentalities.

In testimony that I claim the foregoing as my invention, I have signed my name hereto.

JOSEF HOFMANN.
